ELECTRIC-CONTACT THERMOSTAT.

1,315,601.

Specification of Letters Patent.

Patented Sept. 9, 1919.

Application filed January 19, 1918. Serial No. 212,804.

To all whom it may concern:

Be it known that I, HARRY G. GEISSINGER, a citizen of the United States of America, residing at New York, in the county of New York and State of New York, have invented certain new and useful Improvements in Electric-Contact Thermostats, of which the following is a specification, reference being had therein to the accompanying drawings.

10 The invention relates to thermostats of that type in which the electrical contact is made or broken by the lateral deflection of an arched element in coöperation with a chord or tie element having a different coefficient of expansion. It is the object of the present invention to overcome certain defects of constructions of the type heretofore devised and to render the instrument more sensitive and accurate in its operation and 15 simple in its construction. The invention therefore comprises various features of construction as hereinafter set forth.

In the drawings:

Figure 1 is a plan view through the instrument;

Fig. 2 is a longitudinal section thereof; and

Fig. 3 is a side elevation.

The principle on which the construction is based is the deflection of the arch element by differential expansion due solely to the temperature which is to be controlled. Accuracy is therefore only obtained where there is freedom for movement without frictional or other resistance; where the expansible elements are exposed to free contact with the air; and where the temperature of these elements is unaffected either by independent heat generation or conduction to or from contacts other than that of the air. I have closely approximated the ideal condition,—first, by eliminating friction and providing perfect freedom of action without mechanical restraint; second, by providing full exposure to the air of all the surface of the expansible elements, avoiding any shielding of the one by another; third, by providing sufficient area and mass in the element which forms a portion of the electrical circuit to quickly dissipate whatever heat is electrically generated; fourth, by interposing thermal insulation between the elements and the base on which they are mounted to avoid transfer of heat from the one to the other;

5 fifth, by providing a linkage between the elements having different coefficients of expansion, which secures accuracy in movement without necessitating a high degree of mechanical perfection.

A is a base or supporting frame, which is 60 provided with projecting lugs B and B' for the securing of the ends of a pair of chord elements C and C' arranged parallel to each other and extending in a plane parallel to the base. The opposite ends of these chord elements are connected to each other by a yoke D, which has a flexible portion E for attaching it to the base, so that the chord elements will be maintained in the same plane while being free to adjust themselves 65 in said plane to compensate for expansion and contraction. F is an arch element arranged intermediate the chord elements C and C' in substantially the same plane and differing therefrom as to its coefficient of 70 expansion, the arch being greatly exaggerated for clearness. One end of this arch engages a V-shaped bearing G which is pivotally connected at H to the yoke D and preferably extends through an aperture in 75 the portion E. This aperture may be formed by striking out lugs or ears I from the member E, which act as guides for the ends of the V-shaped bearing G and for the end of the arch member F engaged therewith. Thus 80 the bearing G is self-aligning and at the same time disengagement of the arch is prevented. J is the electrical contact which coöperates with the arch member in the closing and 85 opening of the electrical circuit, said contact being mounted upon the base A and insulated therefrom by the insulating member K. The contact is preferably in the form of a screw passing through the insulator K and adjustable longitudinally by engaging 90 nuts L upon opposite sides of the insulator. M is an insulated terminal post, which is 95 connected with the contact member J through the link N.

It is one of the objects of the invention 100 to provide an adjustment between the arch and the contact J, which is independent of any adjustment of the contact screw. This has the advantage of greater accuracy in setting, as the bearing surface of the contact is seldom in exact axial alignment with the screw and therefore a rotation of the latter will cause a more or less eccentric

movement of the contact. This in turn will produce a lateral movement relative to the contact on the arch member, and as this is seldom in a plane exactly perpendicular to the axis of the screw accurate adjustment by rotation of the screw is difficult. I have avoided the difficulty by providing means for adjusting one end of the arch in a direction perpendicular to the plane thereof, which adjustment will produce a relative movement between the contact on the arch and the fixed contact J. It is essential in this lateral adjustment of the arch to avoid any variation in the length between the ends of the arch, as such variation would change the curvature. It is also essential to provide means for varying the curvature of the arch which is independent of this lateral adjustment, and both of these adjustments are provided for by the construction as follows: B² is a lug intermediate the lugs B and B', which is provided with an oblique or wedge surface forming a bearing for a coöperating wedge member O. The opposite face of the wedge member O is in a plane perpendicular to the plane of the arch and chord elements and forms a bearing for an adjustable block P, which is notched to engage the end of the arch element. Q is a screw passing through a slot in the wedge element O and engaging a threaded bearing in the base A, so as to form a means for adjusting the wedge relative thereto. R is a screw engaging the base and bearing against the block P so as to form a means of adjusting the latter relative to the wedge. Thus by adjusting the screw Q the wedge will be moved to change the curvature of the arch, while by adjusting the screw R the arch will be deflected laterally without altering this curvature. It is necessary to hold the block P in contact with the screw R and also in contact with the face of the wedge member. For this purpose I have provided a pair of links S S' on opposite sides of the lug B² and the wedge O and block P. These links are loosely connected by a pin T which engages a notch in the lug B² and are also connected by a pin U engaging a notch in the block P. The links S S' are bent into the form of a bell-crank lever and at the end of the bent portion is a pin V forming a bearing for a spring W which is anchored to the lug B². The arrangement is such that the tension of the spring W, operating upon the pin V, will first draw the pin U against the block P to hold the latter firmly against the wedge and the wedge against the lug B², and also by fulcruming about the pin T will yieldably press the block P against the screw R. Thus a single spring maintains the block P against both of its bearings and insures the maintenance of relative position of parts when once adjusted.

To make the bearing and block P self-aligning, instead of providing it with a flat face for contact with the wedge O, it is preferably formed with a V-face so as to rock upon a vertical axis. Thus any inaccuracy either in the notch in the bearing or at the end of the arch member will be compensated for automatically.

In use, the instrument is adjusted by first adjusting the screw Q which actuates the wedge E, thereby moving the block P toward or from the arch element to alter the curvature thereof. During this adjustment the block P will be maintained perpendicular to the plane of the elements and in the same relative position to the adjusting screw R, its only movement being a rectilinear one parallel to the plane of the arch. After the curvature of the arch has been thus adjusted the distance between the arch and the contact point J may be adjusted by operation of the screw R. This, by movement of the block P upon the face of the wedge O will swing the arch toward or from the contact J without altering the curvature of the arch. In both of these adjustments the block P is held firmly against its bearing by the tension of the spring W, which coöperates with the links S and S' and pins T, U, V, and presses the block both against the screw R and the face of the wedge.

In operation, the air of the room in which the instrument is located is free to come into contact with both faces of each of the elements C C' and F, and as these elements are in substantially the same plane they will not in any way shield or interfere with each other. When there is a change in temperature, causing either expansion or contraction of the elements C and C' the yoke ends of said elements are free to move relative to the base in their common plane by the flexing of the link E. On the other hand, since the corresponding extremities of the arch and chord elements may not move relatively and they differ as to their coefficients of expansion, a change in temperature can only result in a lateral deflection or change in curvature of the arch so as to adjust the same into or out of contact with the contact member J. When contact is established whatever heat is electrically generated will be quickly distributed by conduction and dissipated through the large air-exposed surface of the member F. As a consequence the opening and closing of the electrical circuit will correspond accurately to predetermined temperature changes in the air which bathes the elements C C' and F.

Where the elements of the thermostat are mounted upon a metal body or frame in good heat conducting relation thereto there will be a lag in operation due to the transfer of heat between the elements and frame. To avoid this objectionable result I have inter-

posed heat insulation so as to materially slow the rate of conduction, thereby rendering the instrument more responsive to atmospheric temperature changes.

- 5 The heat insulation may be obtained by the use of various substances applied in various ways, but as specifically shown X is a heat insulating member arranged between the flexible member E and the base A, and
 10 X' is a heat insulating member between each of the chord elements C and C' and the lugs B and B' to which they are secured. Thus the transfer of heat between the base and the elements of the thermostat is greatly
 15 slowed by the members X and X'.

What I claim as my invention is:

1. In an electric contact thermostat, the combination with an arch element and chord elements arranged in substantially the same
 20 plane, of means for maintaining the chord elements constantly in their plane, a contact member in fixed relation to said plane, and means for laterally adjusting said arch element in relation to said contact member.
 25 2. An electric contact thermostat, comprising an arch element and a pair of chord elements arranged in substantially the same plane, a base on which said elements are mounted, means for connecting the chord
 30 elements to said base to maintain the same constantly in the same plane, an electric contact member mounted on said base and extending into proximity to said arch element, and means for adjusting said arch element
 35 laterally toward or from said contact member and without altering the curvature thereof.

3. An electric contact thermostat, comprising a base, an arch element and a pair of
 40 chord elements arranged in substantially the same plane, means for connecting the chord elements to said base to maintain them constantly in the same plane, a yoke connecting the adjacent ends of the chord elements providing a bearing for the rocking engagement of one end of the arch element, a bearing for the opposite end of said arch element, means for independently adjusting said bearing longitudinally of the arch to alter the curvature thereof and laterally, and a contact normally fixed in relation to the base, toward and from which said arch is moved by the lateral adjustment of said bearing.

4. An electric contact thermostat, comprising a base member, an arch element and a pair of chord elements arranged in substantially the same plane, bearings on said base to which one end of each of said chord elements is rigidly attached, a flexible connection between said base and the opposite ends of said chord elements for maintaining the same in a fixed plane while permitting adjustment in said plane, a yoke between the free ends of said chord elements forming a bearing for one end of the arch element, a

block forming a bearing for the opposite end of said arch element adjustable perpendicular to the plane of said chord and arch elements, a wedge having one face perpendicular to said plane and forming a bearing for 70 said block, a fixed bearing on said base for the opposite face of said wedge, means for adjusting said wedge on said fixed bearing to shift said block and alter the curvature of the arch, and a contact member normally 75 fixed on the base, toward and from which said arch is adjusted by the lateral movement of said block on said wedge.

5. An electric contact thermostat, comprising a base, an arch element and a pair of 80 chord elements arranged in substantially the same plane, means for attaching one end of each of the chord elements rigidly to said base, a flexible connection between the opposite ends of said chord elements and said 85 base for maintaining a fixed plane of said elements while permitting adjustment in said plane, a yoke between said chord elements forming a bearing for one end of the arch element, a block forming a bearing for 90 the opposite end of said arch element, a wedge having one face perpendicular to the plane of said elements, forming a bearing for said block, an inclined bearing on said base for the opposite face of said wedge, independent means of adjusting said wedge upon its bearing on the base and for adjusting said block upon said wedge, and means for yieldably pressing said block against said wedge and the adjustment means there- 95 for.

6. An electric contact thermostat, comprising a base, an arch element and a pair of chord elements arranged in substantially the same plane, one end of each of the chord 105 elements being rigidly attached to said base, a flexible connection between the opposite ends of said chord elements and said base permitting adjustment thereof to maintain the plane of said elements, a yoke connecting the adjustable ends of said chord elements, a bearing for said arch element on said yoke, a wedge having an oblique bearing on said base and provided with a face perpendicular to the plane of said elements, 110 a screw for adjusting said wedge toward or from said base, a block forming a bearing for the opposite end of said arch element and slidably engaging the perpendicular face of said wedge, a screw in said base for 115 adjusting said block upon said wedge, a pair of links embracing said block and wedge, and a tensioning device operating through said links for holding said block against said wedge and also against the adjusting screw 120 for the block.

7. In an electric contact thermostat, an arch element and a chord element having different coefficients of expansion, arranged in substantially the same plane, and a 130

mounting for said elements having a rigid connection with one end thereof and a flexible connection to the opposite end.

8. An electric contact thermostat, comprising an arch element and a pair of chord elements arranged in substantially the same plane, the arch element being intermediate the chord elements, a connection between the corresponding ends of said elements, and 10 a self-aligning bearing for said arch element upon said connection.

9. In an electric contact thermostat, an arch element and a pair of chord elements arranged in substantially the same plane, 15 connections between the corresponding opposite ends of said elements, and self-aligning bearings on said connections for said arch elements.

10. In an electric contact thermostat, an arch element and a pair of chord elements arranged in substantially the same plane with the arch element centrally between said chord elements, connections between the corresponding opposite ends of said elements, means for adjusting one end of said arch element on its connection, a mounting for said elements rigidly attached to one of the connected ends thereof, and a flexible connection between said mounting and the opposite connected end of said elements to permit movement thereof only in their plane.

11. In an electric contact thermostat, an

arch element and a chord element having different coefficients of expansion, arranged in substantially the same plane, a base or 35 mounting for said elements having a rigid connection therewith at one end, a flexible connection between the opposite end of said elements and said base, permitting freedom of movement in their common plane, and a 40 bearing for said arch element adjustable on said mounting in said common plane.

12. An electric contact thermostat, comprising an arch element and a pair of chord elements arranged on opposite sides thereof 45 in substantially the same plane, a mounting having a rigid connection to one end of each of the pair of chord elements, a yoke connecting the opposite ends of the pair of chord elements, a flexible connection between said yoke and the mounting for maintaining said chord elements in the same plane while permitting movement of the yoke in said plane, a V-shaped bearing 50 pivotally connected to said yoke and having a self-aligning engagement with the end of said arch element, and a V-shaped bearing having a self-aligning engagement with the opposite end of said arch element, and means for adjusting the latter bearing to 55 alter the curvature of the arch.

In testimony whereof I affix my signature.

HARRY G. GEISSINGER.
